US00D915887S

(12) **United States Design Patent** (10) **Patent No.:** **US D915,887 S**
(45) **Date of Patent:** **** Apr. 13, 2021**

(54) **BOTTLE**

(71) Applicant: **PepsiCo, Inc.**, Purchase, NY (US)

(72) Inventors: **Emilian D. Cartis**, London (GB);
William R. Eaton, Southbury, CT (US); **Niklas Gustafsson**, New York, NY (US); **Kamal Mahajan**, Tarrytown, NY (US); **Charles White**, Parsippany, NJ (US)

(73) Assignee: **PepsiCo, Inc.**, Purchase, NY (US)

(**) Term: **15 Years**

(21) Appl. No.: **29/739,187**

(22) Filed: **Jun. 23, 2020**

Related U.S. Application Data

(63) Continuation of application No. 29/664,761, filed on Sep. 27, 2018, now Pat. No. Des. 889,264, which is a continuation of application No. 29/601,442, filed on Apr. 21, 2017, now Pat. No. Des. 829,556.

(74) *Attorney, Agent, or Firm* — Sterne, Kessler, Goldstein & Fox P.L.L.C.

(57) **CLAIM**

The ornamental design for a bottle, as shown and described.

DESCRIPTION

FIG. 1 is a top perspective view of a bottle showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the bottle that form no part of the claimed design.

The dot-dash broken lines in the figures show boundaries that form no part of the claimed design.

1 Claim, 7 Drawing Sheets
